UNITED STATES PATENT OFFICE.

WILBERT STEVENS BIRDSALL, OF BROOKLYN, NEW YORK.

MANIFOLDING SALES-BOOK.

1,194,938.

Specification of Letters Patent. Patented Aug. 15, 1916.

Application filed July 14, 1915. Serial No. 39,931.

To all whom it may concern:

Be it known that I, WILBERT STEVENS BIRDSALL, a citizen of the United States, residing at Brooklyn, Kings county, New York, have invented a new and useful Manifolding Sales-Book, of which the following is a specification.

This invention relates to salesbooks, and the main object of the invention, is to provide a certain construction and arrangement of the leaves and carbons, whereby a single writing will produce a copy on three sections of paper, as illustrated in the accompanying drawings which show the invention.

The accompanying drawing shows the invention.

Figure 1 is a perspective view illustrating the improved book, certain of the sheets being raised for the sake of clearness. Fig. 2 is a side view of the construction shown in Fig. 1.

Fig. 1, is a perspective view of the book, with both carbons being shown turned back to show their relation to the pile of sheets, which are piled up in the manner usual to salesbooks, by one sheet being folded on top of the others designated by letter A.

This invention bears a slight resemblance to Patent 1,147,922, July 27, 1915, but is different in matter of construction as per following description.

Leaves indicated by D and E are comprised of one single sheet of paper, folded, at about the middle of its length and perforated at or near the line of fold, and printed and numbered.

Section F, the triplicate, is attached at

one end to the stub portion and back of book, the other end being pasted to the back or outside of sheet E, near its fold and perforation G, said pasting being the connection between the leaves D and E and section F. Section F holds the triplicate set in its relation to the carbons, and is perforated at stub to be easily torn out, and is preferably of a much heavier material than D—E, and may be as heavy as 100 lb. tag Manila board, and serve as a firm foundation for the writing on the original sheet D, doing away with the necessity of inserting a separator. This sheet is printed and numbered the same as D—E or may be blank and can be punched with one or more holes I, for the purpose of facilitating tying to packages, for the purpose of insuring proper delivery of the article.

The carbon sheets B and C are attached to stub portion and back, that they may be inserted between sheets D and E, when writing is made on the original to secure duplicate and triplicate copies.

I claim:

A triplicate salesbook comprising a series of sets of leaves, each set consisting of an original and duplicate formed of an integral sheet of paper folded and pasted at its fold to the free end of the third leaf which is perforated to form a stub, said stubs being fastened together, and carbon sheets attached to the pile of stubs for insertion between the leaves.

WILBERT STEVENS BIRDSALL.

In presence of—

GEORGE MERGLE,
ROBERT FRITH.
